tion of California

Filed May 7, 1962, Ser. No. 192,691
5 Claims. (Cl. 208—59)

This invention relates to new techniques for the operation of multi-stage hydrocracking processes, so as to produce therefrom both a relatively high-octane gasoline product, and a relatively non-aromatic, low-freezing-point jet fuel product. In its simplest modification, the invention embraces two stages of hydrocracking, the first stage being operated under optimum conditions for producing relatively high-octane gasoline, and the second stage being operated under optimum conditions for the production of high-quality jet fuels. The optimum conditions referred to for each stage involve a proper selection of temperatures, pressures, catalysts, feedstocks, and most importantly to this particular invention, an optimum selection of specific recycle fractions for each of the hydrocracking stages.

Briefly stated, the invention comprises the following steps: (1) a gas oil feedstock is subjected to a first stage of hydrocracking at relatively high temperatures, permissibly in the presence of contaminants such as hydrogen sulfide and/or ammonia; (2) the effluent from the first-stage hydrocracking is fractionated to recover a relatively high-octane gasoline product, an intermediate-boiling-range light gas oil, and a high-boiling bottoms fraction; (3) the light gas oil is recycled to the first hydrocracking stage; (4) the bottoms fraction is sent to a second hydrocracking stage which operates at relatively lower temperatures and substantially in the absence of nitrogen and sulfur compounds; (5) the effluent from the second hydrocracking stage is fractionated to recover a small amount of light gasoline boiling up to about 350° F., a desired jet fuel product fraction, and a heavy gas oil bottoms fraction; and (6) the heavy gas oil bottoms fraction is either utilized as diesel fuel or recycled to the second hydrocracking stage. It is found that by operating in this manner, with recycle of a light gas oil to the first stage, and only heavier gas oils to the second stage, higher quality jet fuels, and larger quantities of high-octane gasoline are obtained, as compared to a case where there is no recycle of unconverted oil to the first hydrocracking stage, i.e., a case where all of the unconverted oil from the first stage boiling above the gasoline range is treated exclusively in the second stage.

According to a preferred modification of the invention, where the initial feed contains substantial amounts of nitrogen and/or sulfur compounds, the first hydrocracking stage is preceded by an "integral" hydrofining treatment. In this pretreatment step, the feed is contacted with a hydrofining catalyst under conditions of temperature and pressure similar to those prevailing in the first hydrocracking stage, to thereby convert organic sulfur and nitrogen compounds to hydrogen sulfide and ammonia. The total effluent from the hydrofining step is then transferred directly to the first hydrocracking stage without intervening treatment for the removal of ammonia and/or hydrogen sulfide. It has been found that hydrogen sulfide in the first hydrocracking stage is beneficial from the standpoint of improving the octane number of the gasoline produced therein.

In copending application Serial No. 134,935, filed August 30, 1961, now U.S. Patent No. 3,132,087, it is shown that in two-stage hydrocracking processes, where the unconverted oil from the first stage is treated in the second stage, a higher octane gasoline is produced in the

2

first stage than in the second stage, and that the jet fuel fraction produced from the second stage is superior to the jet fuel fraction from the first stage. The present invention is based upon our discovery that larger quantities of high octane gasoline are recoverable from the first stage, and still higher quality jet fuels are recoverable from the second stage, if the light gas oil product fraction from the first stage is recycled back to that stage instead of being transferred to the second stage. The explanation for these improved results is not entirely clear, but a partial explanation may be found in the following factors:

Firstly, in order to produce low-freezing-point jet fuels it is necessary to reduce the content of normal paraffins and aromatics, and increase the isoparaffin and naphthalene content. Virgin jet fuel fractions are relatively rich in normal paraffins, while jet fuel fractions produced by the hydrocracking of oils boiling above the jet fuel range, i.e., completely synthetic jet fuels, are relatively richer in isoparaffins as compared to normal paraffins.

As a result of eliminating the light gas oil fraction from the feed to the second stage, all of the jet fuel produced therein will be synthetic, i.e., produced from hydrocarbons boiling above the jet fuel range, and will consequently be richer in isoparaffins.

Secondly, by recycling the light gas oil product fraction from the first hydrocracking stage back to that stage, the total feed thereto, i.e., fresh feed plus recycle, becomes relatively rich in hydrocarbons boiling between about 400° and 550° F., and relatively lean in hydrocarbons boiling above 550° F. The hydrocracking conditions in the first stage can then be adjusted more selectively to minimize hydrogenation and thus increase aromaticity of the gasoline produced. This entails using somewhat lower pressures and/or higher temperatures, factors which normally tend to cause a more rapid deactivation of the catalyst. But since deactivation is due largely to the presence of heavy aromatic hydrocarbons boiling above 550° F., and since the concentration of these hydrocarbons is reduced by the recycle dilution, their deactivating effect is also minimized. Consequently, it will be seen that, as a result of the recycle to the first stage, each stage of the hydrocracking can be adjusted more selectively, so as to produce even more highly aromatic gasolines from the first stage, and more highly naphthenic and isoparaffinic jet fuels from the second stage.

From the foregoing it will be apparent that the principal purpose of this invention is to provide an integrated hydrocracking process designed mainly for the production of high-octane gasoline, but which can also produce a high-quality, low-freezing-point jet fuel, boiling for example in the 350–550° F. range. A specific object is to provide a hydrocracking process which will produce jet fuels having a freezing point below about –60° F. Other objects will be apparent from the more detailed description which follows.

The invention may perhaps be more readily understood with reference to the attached drawing, which is a flowsheet illustrating a preferred form of the invention. The initial feedstock is brought in via line 2, mixed with recycle light gas oil from line 3 (if desired), and with recycle and makeup hydrogen from line 4. The mixture is then preheated to incipient hydrofining temperature in heater 6, and passed directly into hydrofiner 8, where hydrofining proceeds under substantially conventional conditions. Suitable hydrofining catalysts include for example mixtures of the oxides and/or sulfides of cobalt and molybdenum, or of nickel and tungsten, preferably supported on a carrier such as alumina, or alumina containing a small amount of coprecipitated silica gel. Other suitable catalysts include in general the oxides and/or sulfides of the Group VIB and/or Group

VIII metals, preferably supported on adsorbent oxide carriers such as alumina, silica, titania, and the like. The hydrofining operation may be conducted either adiabatically or isothermally, and under the following general conditions:

Hydrofining conditions

	Operative	Preferred	
Temperature, ° F.....	600-850	650-750	10
Pressure, p.s.i.g.....	500-3,000	800-2,000	
LHSV, v./v./hr.....	0.5-10	1-5	
H ₂ /oil ratio, s.c.f./b.....	500-15,000	1,000-10,000	

The above conditions are suitably adjusted so as to reduce the organic nitrogen content of the feed to below about 25 parts per million, and preferably below about 10 parts per million.

The total hydrofined product from hydrofiner 8 is taken off in line 10 and transferred via heat exchanger 12 to first-stage hydrocracker 14, without intervening condensation or separation of products. Heat exchanger 12 is for the purpose of suitably adjusting the temperature of feed to hydrocracker 14; this may require either cooling or heating, depending upon the respective hydrofining and hydrocracking temperatures employed. Inasmuch as first-stage hydrocracker 14 and hydrofiner 8 are preferably operated at essentially the same pressure, it is entirely feasible to enclose both contacting zones within a single reactor, using appropriate temperature control means.

The process conditions in hydrocracker 14 are suitably adjusted so as to provide about 20-70% conversion to 400° F. end-point gasoline and lighter products per pass, while at the same time permitting relatively long runs between regenerations, i.e., from about 2 to 8 months. For these purposes, as well as for maintaining product quality within the 85-100 octane range (F-1+3 ml. TEL), it will be understood that temperatures in the high range will be used in connection with pressures in the high range, while the lower temperatures will normally be used in conjunction with lower pressures. The range of operative conditions contemplated for reactor 14 are as follows:

First-stage hydrocracking conditions

	Operative	Preferred	
Temperature, ° F.....	500-850	600-800	
Pressure, p.s.i.g.....	400-3,000	500-2,000	
LHSV, v./v./hr.....	0.5-10	1-5	
H ₂ /oil ratio, s.c.f./b.....	500-15,000	1,000-10,000	

The effluent from hydrocracker 14 is withdrawn via line 16, condensed in condenser 18, then mixed with wash water injected via line 20 into line 22, and the entire mixture is then transferred to high-pressure separator 24. Recycle hydrogen is withdrawn via line 26, and aqueous wash water containing dissolved ammonia and hydrogen sulfide is withdrawn via line 28. The liquid hydrocarbon phase in separator 24 is flashed via line 30 into low-pressure separator 32, from which flash gases 60 comprising methane, ethane, propane and the like are withdrawn via line 34. The liquid hydrocarbons in separator 32 are then transferred via line 36 to fractionating column 38.

In fractionating column 38, the first-stage hydrocracking effluent is split into three fractions, as follows:

(1) A 350-400° F. end-point gasoline fraction which is taken overhead via line 40. This gasoline will have an octane number (F-1+3 ml. TEL) of about 85-100, and may in many cases be used directly as blending stock for high octane gasolines. In other cases, it may be desirable to subject it to a mild reforming operation to gain still further octane improvement.

(2) A light gas oil side-cut fraction, which is taken off via line 42 and recycled either to raw feed line 2 as 75

previously described, or preferably to line 10 via line 44 for direct treatment in first stage hydrocracker 14, thus by-passing hydrofiner 8. Normally this recycle oil does not require further hydrofining, and a higher octane gasoline product is obtained by by-passing the hydrofiner. The initial boiling point of this side-cut fraction will be determined by the desired end-boiling-point of the gasoline fraction which was recovered, and will thus be between about 350° and 400° F. The end-boiling-point of the side-cut should preferably fall within about ±20° F. of the desired end-boiling-point of the jet fuel product to be produced from the second stage hydrocracker. Since most commercial grades of jet fuels have an end-boiling-point which lies between about 500° and 550° F., the end-boiling-point of the side-cut in line 42 will preferably also fall within that range. In this manner, substantially all of the jet fuel synthesized in the second-stage hydrocracker will be derived from hydrocarbons boiling above the end-boiling-point of the desired jet fuel product. Broadly however, it is contemplated that any selected fraction of the first-stage product, which fraction boils within the boiling range of the desired jet fuel product, may be recycled to the first stage.

(3) A bottoms fraction from column 38 is recovered via line 46, and comprises the remaining hydrocarbons boiling above the end-boiling-point of the side-cut in line 42. Thus, the initial boiling point of the bottoms fraction will normally be between about 500° and 550° F., this constituting the primary feedstock to the second-stage hydrocracker.

The bottoms fraction in line 46 is then blended with second-stage recycle oil from line 48, and this combined feed in line 50 is then mixed with recycle and makeup hydrogen from line 52, preheated to incipient hydrocracking temperatures in heater 54, and passed into second-stage hydrocracker 56. This feedstock differs considerably from the feed to the first stage hydrocracker in that it is substantially free of nitrogen compounds and has a higher initial boiling point. It is also substantially free of sulfur compounds, and hence the second-stage hydrocracker may be operated entirely sweet if desired by simply removing hydrogen sulfide from the recycle gas to that stage. Ordinarily, it is preferred to operate the second stage sweet, in order to maintain the hydrogenating component on the catalyst in a metallic state, the metallic state normally being the most active form for hydrogenation. Moreover, due to the substantial absence of nitrogen compounds, and the objective of maximizing jet fuel production rather than gasoline, lower temperatures can be maintained in hydrocracker 56. The process conditions in hydrocracker 56 are preferably adjusted so as to provide from 40-80% conversion to jet fuel and lighter products per pass. To achieve this objective, the hydrocracking conditions should be suitably correlated within the following general ranges:

Second-stage hydrocracking conditions

	Operative	Preferred
Temperature, ° F.....	400-750	500-700
Pressure, p.s.i.g.....	500-3,000	800-2,000
LHSV, v./v./hr.....	0.5-15	1-10
H ₂ /oil ratio, s.c.f./b.....	500-15,000	2,000-12,000

At the conversion levels and conditions prescribed for the second-stage hydrocracker, the run length between catalyst regenerations can be adjusted to coincide substantially with the run length in reactor 14, e.g., between about 2 and 8 months. In extended runs such as these, it is normally desirable to maintain substantially constant conversion in each stage by incrementally raising the temperature as the activity of the catalyst declines. The rate of catalyst activity decline in reactors 14 and 56 under the prescribed conditions is such that constant

conversion in both reactors can be obtained by raising the respective temperatures between about 0.1 and 3° F. per day, on the average. The average temperature in hydrocracker 56 will normally be about 50-200° F. lower than the average temperature in hydrocracker 14.

The total effluent from hydrocracker 56 is withdrawn via line 58, condensed in cooler 60 and transferred to high pressure separator 62, from which recycle hydrogen is withdrawn via line 64. The condensed hydrocarbons in separator 62 are then flashed via line 66 into low pressure separator 68, from which flash gases are exhausted via line 70. The liquid hydrocarbon product in separator 68 is withdrawn via line 72 and transferred to second-stage product fractionation column 74, wherein it is fractionated into gasoline, jet fuel and bottoms recycle fractions, as in column 38. A small proportion of light gasoline blending stock is withdrawn as overhead via line 76, and a jet fuel side-cut product fraction via line 78. This jet fuel product will normally have an initial boiling point between about 300° and 400° F., an end-boiling-point between about 500° and 550° F., and a freezing point between about -65° and -100° F. The bottoms from column 74 is taken off in line 80, and may be withdrawn from the system via line 82 and utilized as diesel fuel, or it may be recycled via line 48 to second-stage hydrocracker 56 as previously noted. It will be understood that the choice of these alternatives depends largely upon the desired refinery balance and market demands.

The hydrocracking catalysts to be employed in the hydrocracking units described above may consist of any desired combination of a refractory cracking base with a suitable hydrogenating component. Suitable cracking bases include for example mixtures of two or more refractory oxides such as silica-alumina, silica-magnesia, silica-zirconia, alumina-boria, silica-titania, silica-zirconia-titania, acid treated clays and the like. Acidic metal phosphates such as aluminum phosphate may also be used. The preferred cracking bases comprise composites of silica and alumina containing about 50-90% silica; coprecipitated composites of silica, titania, and zirconia containing between 5% and 75% of each component; partially dehydrated, zeolitic, crystalline molecular sieves, e.g., of the "X" or "Y" crystal types, having relatively uniform pore diameters of about 8 to 14 Angstroms, and comprising silica, alumina and one or more exchangeable zeolitic cations. Any of these cracking bases may be further promoted by the addition of small amounts, e.g., 1 to 10% by weight, of halogen or halides such as fluorine, boron trifluoride or silicon tetrafluoride.

The molecular sieve type cracking bases, when compounded with a hydrogenating metal, are particularly useful for hydrocracking at relatively low temperatures of 400-700° F., and relatively low pressures of 500-1,500 p.s.i.g. It is preferred to employ molecular sieves having a relatively high $\text{SiO}_2/\text{Al}_2\text{O}_3$ ratio, e.g., between about 2.5 and 6.0. The most active forms are those wherein the exchangeable zeolitic cations are hydrogen and/or a divalent metal such as magnesium, calcium or zinc. In particular, the "Y" molecular sieves, wherein the $\text{SiO}_2/\text{Al}_2\text{O}_3$ ratio is about 5, are preferred, either in their hydrogen (or "decationized") form, or a divalent metal form, preferably magnesium. Normally, such molecular sieves are prepared first in the sodium or potassium form, and the monovalent metal is ion-exchanged out with a divalent metal, or where the hydrogen form is desired, with an ammonium salt followed by heating to decompose the zeolitic ammonium ion and leave a hydrogen ion. It is not necessary to exchange out all of the monovalent metal; the final compositions may contain up to about 6% by weight of NaO , or equivalent amounts of other monovalent metals. Catalysts of this nature are more particularly described in Belgian Patents Nos. 598,582, 598,682, 598,683 and 598,686.

As in the case of the X molecular sieves, the Y sieves

75

also contain pores of relatively uniform diameter in the individual crystals. In the case of X sieves, the pore diameters may range between about 6 and 14 Å., depending upon the metal ions present, and this is likewise the case in the Y sieves, although the latter usually are found to have crystal pores of about 9 to 10 Å. in diameter.

The foregoing cracking bases are compounded, as by impregnation, with from about 0.5 to 25% (based on free metal) of a Group VIB or Group VIII metal promoter, e.g., an oxide or sulfide of chromium, tungsten, cobalt, nickel, or the corresponding free metals, or any combination thereof. Alternatively, even smaller proportions, between about 0.05% and 2% of the metals platinum, palladium, rhodium or iridium may be employed. The oxides and sulfides of other transitional metals may also be used, but to less advantage than the foregoing.

In the case of the zeolitic type cracking bases, it is preferable to distribute the hydrogenating metal thereon by ion exchange. This can be accomplished by digesting the zeolite with an aqueous solution of a suitable compound of the desired hydrogenating metal wherein the metal is present in a cationic form, and then reducing to form the free metal, as described for example in Belgian Patent No. 598,686.

The feedstocks which may be treated herein include in general any mineral oil fraction having an initial boiling point above the conventional gasoline range, i.e., above about 400° F., and having an end-boiling-point above the end-boiling-point of the desired jet fuel product, and up to about 1,000° F. This includes straight-run gas oils, coker distillate gas oils, deasphalted crude oils, cycle oils derived from catalytic or thermal cracking operations and the like. These fractions may be derived from petroleum crude oils, shale oils, tar sand oils, coal hydrogenation products and the like. Specifically, it is preferred to employ feedstocks boiling between about 400° and 900° F., having an API gravity of about 15° to 35°, containing at least about 20% by volume of acid-soluble components (aromatics+olefins), and at least about 20% by volume of hydrocarbons boiling above 650° F. Such oils may also contain from about 0.1% to 5% of sulfur and from about 0.001% to 2% by weight of nitrogen.

The following example is cited to illustrate the process as above-described in connection with the drawing, but should not be construed as limiting in scope:

EXAMPLE

In this example, a blend of delayed coker distillate and thermally cracked gas oils derived from California crude oils is utilized as feed. The treatment comprises an initial catalytic hydrofining, with the total hydrofining effluent passing to the first stage of hydrocracking. The first-stage hydrocracking effluent is water-washed and fractionated to recover a 400° F. end-point gasoline fraction, a 405-510° F. light gas oil fraction which is recycled to the first stage, and a bottoms fraction which is fed to the second stage of hydrocracking. The effluent from the second hydrocracking stage is condensed and separately fractionated to recover a 350° F. end-point light gasoline fraction, a 360-510° F. jet fuel fraction and a bottoms fraction, the latter being recycled to the second stage of hydrocracking. The significant conditions, specifications and results of the process are as follows:

Initial feedstock:

Boiling range, ° F. -----	400-850
Acid-solubles, vol. percent -----	65
Gravity, ° API -----	21
Nitrogen, wt. percent -----	0.4
Sulfur, wt. percent -----	2

Hydrofining conditions:

Catalyst: 3% CoO , 15% MoO_3 on 5% SiO_2 -95% Al_2O_3 carrier; catalyst presulfidized.

Temperature, avg. bed, ° F. ----- 705

Pressure, p.s.i.g. ----- 1,500

The leaded octane number of the first-stage C ₇ -400° F. gasoline is about 94-98, and the freezing point of the second-stage jet fuel is about -75° F. If the entire first-stage product fraction boiling above 400° F. were sent to the second stage, the freezing point of the 360-510° F. jet fuel product would be about -50° F.		
Results analogous to those indicated in the foregoing example are obtained when other hydrocracking catalysts and conditions, other feedstocks and other hydrofining conditions within the broad purview of the above disclosure are employed. It is hence not intended to limit the invention to the details of the example or the drawing, but only broadly as defined in the following claims.		
We claim:		
1. An integrated process for the manufacture of high-octane gasoline and high-quality jet fuel by hydrocracking which comprises: (1) subjecting a gas oil feedstock containing hydrocarbon components boiling above the end-point of the desired jet fuel product, and also containing organic sulfur and/or nitrogen compounds, to catalytic hydrofining to effect decomposition of said sulfur and nitrogen compounds; (2) subjecting effluent from said hydrofining, without intervening treatment for the removal of ammonia and hydrogen sulfide, to a first stage of catalytic hydrocracking at a temperature between about 500° and 850° F. and a pressure between about 400 and 3,000 p.s.i.g., said temperature being adjusted to give a 20-70% conversion per pass to 400° F. end-point products; (3) treating the effluent from said first-stage hydrocracking to separate out water-soluble sulfur and nitrogen	45	60

compounds; (4) fractionating the hydrocarbon product from said first-stage hydrocracking to recover (a) a gasoline product fraction having an end-boiling-point above about 350° F., (b) a light gas oil fraction boiling above said gasoline product fraction and having an end-boiling-point between about 500° and 550° F., and (c) a heavy gas oil boiling above the end-boiling-point of said light gas oil fraction and above the end-boiling-point of the desired jet fuel product; (5) recycling said light gas oil to said first hydrocracking stage; (6) subjecting said heavy gas oil to a second stage of catalytic hydrocracking in the presence of a Group VIII metal-molecular sieve zeolite type hydrocracking catalyst, and at a temperature which is (a) between about 400° and 750° F., and (b) lower than the temperature employed in said first-stage hydrocracking, and at a space velocity adjusted to give about 40 to 80% conversion to jet fuel and lighter products per pass; (7) fractionating the effluent from said second-stage hydrocracking to recover a light gasoline fraction, a jet fuel product fraction having an initial boiling point between about 300° and 400° F., an end-boiling point between about 500° and 550° F., and having a freezing point below about -60° F. which is withdrawn from the process, and a heavy bottoms fraction; and (8) recycling at least a portion of said heavy bottoms fraction to said second hydrocracking stage.

2. A process as defined in claim 1 wherein said first stage of hydrocracking is conducted at a temperature between about 50° and 200° F. higher than the temperature in said second-stage hydrocracking.

3. A process as defined in claim 1 wherein said second-stage hydrocracking is carried out substantially in the absence of sulfur and nitrogen compounds.

4. A process as defined in claim 1 wherein the hydrocracking in each of said stages is carried out at a pressure below about 3,000 p.s.i.g.

5. A process as defined in claim 1 wherein a hydrocracking catalyst comprising a dehydrated, zeolitic molecular sieve of the "Y" crystal type containing zeolitic cations from the group consisting of hydrogen and divalent metals, and promoted with a Group VIII noble metal hydrogenating component, is used in each of said hydrocracking stages.
